United States Patent Office.

WILLIAM BOYD, OF HARTFORD, NEW YORK.

Letters Patent No. 78,418, dated June 2, 1868.

IMPROVEMENT IN MACHINE FOR BENDING CIRCLES.

The Schedule referred to in these Letters Patent and making part of the same.

TO ALL WHOM IT MAY CONCERN:

Be it known that I, WILLIAM BOYD, of Hartford, in the county of Washington, and State of New York, have invented a new and useful Improvement in Machines for Bending Carriage-Circles; and I do hereby declare that the following is a full, clear, and exact description thereof, which will enable others skilled in the art to make and use the same, reference being had to the accompanying drawings, forming part of this specification, in which—

Figure 1 is a top view of my invention.

Figure 2 is a section of the same, through the line *x x* of fig. 1.
Similar letters of reference indicate like parts.

The object of this invention is to perform the bending of the irons generally known as carriage-circles, or fifth-wheels. It consists of the devices set forth in the following:

In the drawings, the circular table A is formed with a succession of circular faces, *a a a*, &c., decreasing in diameter from the bottom upward, by which arrangement several different-sized circles can be formed in the same machine.

The bending is accomplished by means of the wheels H and I, the planes of which are at right angles to each other.

The wheel I is grooved, and is for the purpose of holding the rod N, being bent into a circle, down upon the horizontal part of one of the circular faces.

The wheel H is for the purpose of bending the rod around and against the vertical part of the circular face which is next adjacent. These wheels are borne around the table A, and thus complete the formation of the fifth-wheel or circle.

The wheel H revolves in the standard G, the upper end of which latter is clamped firmly to the lever B, by means of nuts *i j*, which work on a screw-thread cut in the standard, G.

The wheel I works within a yoke, J, which is pivoted to a standard, O, having nuts *k n*. These standards are held within the slot *l*, in the lever B, and are adjustable to or from the table, as will be obvious.

The lever is composed of the two parts, B and E, hinged together at D, for the purpose of raising the wheels to get the rod or bar under them.

This hinge-joint is stiffened by the plate *o*, held under the straps *q p*. The lever turns in the shaft *r*, which is affixed to the part E by a nut, *f*, and the said shaft passes down through the hollow upright, K, cast on or affixed to the table A.

A nut, *e*, serves to hold the shaft in place. The counter-wheel L, working in the yoke-standard, M, which latter is affixed to the part E, by nuts *g* and *h*, rolls upon the plane of the table, and being on the opposite side of the shaft from the other wheels, serves to keep them firmly in contact with the rod or bar being bent.

Set-screws *b b* working in a plate, *d*, serve to hold the end of the said rod or bar.

By withdrawing the pin *s*, the wheel I can be raised upward, to pass it over the clip usually formed on the bottom circle or fifth-wheel, and which clip is formed before the rod is bent to form the circle.

C is the lever-handle. The manner of bending the bar N is shown at fig. 1.

Having thus described my invention, I claim as new, and desire to secure by Letters Patent—

The wheels H I L, table A, and jointed lever C B E, set-screws *b b*, and circular faces *a a a*, all constructed and operating substantially as and for the purpose shown and described.

Witnesses:

ELI C. BRAYTON,

MANUEL N. McDONALD.

WILLIAM BOYD.
